United States Patent Office

Des. 194,503
Patented Feb. 5, 1963

194,503

ELECTRONIC DATA CONVERTER OR SIMILAR ARTICLE

Donald A. Moore, San Jose, Calif., assignor to International Business Machines Corporation, New York, N.Y., a corporation of New York

Filed Mar. 6, 1961, Ser. No. 64,154

Term of patent 14 years

(Cl. D26—5)

FIG. 1

FIG. 2

FIG. 1 is a front perspective view of an electronic data converter or similar article showing my new design; and FIG. 2 is an enlarged fragmentary view thereof.

The dominant features of my new design are shown in solid lines in the drawing.

I claim:

The ornamental design for an electronic data converter or similar article, as shown and described.
